THERMOSTATIC SWITCH

Henry David Epstein, Cambridge, Mass., assignor to
Texas Instruments Incorporated, Dallas, Tex., a cor-
poration of Delaware

Filed Feb. 26, 1959. Ser. No. 795,792

14 Claims. (Cl. 200—138)

This invention relates to thermostatic switches and more particularly to thermostatic switches for insertion into small spaces such as in and about motor windings.

Briefly, the present invention provides an inexpensive small sealed thermostatic switch for protecting motor windings, and the like, comprising a container of two parts separated by an electrically nonconductive layer, and a thermostatic member in the container attached to one of the parts and positioned to close a circuit with the other part of the container.

Among the objects of the present invention are the provision of thermostatic switches useful for protecting motor windings; the provision of switches for this purpose which may be economically constructed and, if desired, sealed in connection with motor windings; the provision of such switches which are composed of a low number of parts which can be easily assembled; the provision of such switches which can be conveniently calibrated as a step in assembly; and the provision of switches of the type indicated which are small in size yet effective for the purpose intended. Other objects and features will be in part apparent and in part pointed out hereinafter.

The invention accordingly comprises the construction hereinafter described, the scope of the invention being indicated in the following claims.

In the accompanying drawings, in which one of various possible embodiments of the invention is illustrated,

FIG. 1 is a much enlarged side elevation of a thermostatic switch made according to the present invention;

FIG. 2 is a top plan of the thermostatic switch;

FIG. 3 is an axial section taken on line 3—3 on FIG. 2;

FIG. 4 is a cross section taken on line 4—4 on FIG. 2;

FIG. 5 is a plan view of the insulating element;

FIG. 6 is a view similar to FIG. 3 but exaggeratedly illustrating calibration of the device prior to completing its construction; and,

FIG. 7 is a fragmentary view similar to FIG. 3 but illustrating a different way of calibrating the device.

Corresponding reference characters indicate corresponding parts throughout the several views of the drawings.

Referring now to the drawings, the thermostatic switch 1 of the present invention includes a container comprising two parts 3 and 5, both constructed of heat conductive material such as metal. The parts 3 and 5 are formed to form a hollow shell or capsule 7 and have projecting flat rim parts 8 and 10 ending in ears 9 and 11 respectively for making electrical connections. Parts 3 and 5 also have peripheral flanges 12 and 14 respectively, located substantially in the planes of the respective flat parts 8 and 10. Parts 3 and 5 sandwich an electrical insulating window member or washer 13 (see FIG. 5) which may be constructed of any suitable electrically nonconductive material. "Mylar" polyester film is a suitable material for this purpose. Member 13 is formed with an opening 15 to accommodate the contact bearing end 17 of thermostatic member 19. Thermostatic member 19 conveniently carries a conventional contact button 21 for engagement with the interior of part 5. Part 5 is coated with an electrical contact material such as silver at the surface area 23 for this purpose.

While not restricted thereto, thermostatic element 19 is preferably made of bimetal and includes a dished portion 25 for imparting snap action to this element. It will

2

be noted that thermostatic element 19 is attached to the terminal 9 of part 3 of the container and is therefore in conductive electrical engagement therewith. It is separated from part 5 of the container by insulator 13 except for the portion of the thermostatic element which projects through opening 15 to make and break electrical contact with part 5 through button 21 and conductive surface 23.

The thermostatic switch of the present invention is conveniently assembled by applying a synthetic resin (epoxy resin for example) to both sides of insulator washer 13, placing the two parts of the container on either side thereof as shown in the drawing and then curing the epoxy resin. For this purpose a thermosetting epoxy resin is particularly desirable and this is allowed to cure and set in place after the parts of the switch have been assembled and calibrated. The parts are preferably further held together by wrapping a layer of "Mylar" film tape around the terminals 9 and 11 at the region 27. This not only renders the assembly more sturdy but facilitates holding the parts together during curing. The tape around area 27 is preferably also held in place with a thermosetting epoxy resin.

Because of the capsule shape of parts 3 and 5 when assembled, the switch may be conveniently calibrated during assembly by slidable adjustment of parts 3 and 5 on the adjacent substantially coplanar flange-forming portions (8, 12) and (10, 14). FIG. 6 illustrates such a device after calibration effected by slidingly changing the relative position of parts 3 and 5. By sliding part 3 with respect to part 5 before the resin is set, the tension placed upon thermostatic member 19 is changed by the cam-like action of the sloping surface 23 relative to contact 21.

FIG. 7 illustrates another way of calibrating the switch either in lieu of or in addition to the method described above. By dimpling part 5 at the point 29, the point where contact 21 meets area 23, the tension placed upon thermostatic member 19 is also changed. If desired, calibration may be effected by a combination of such dimpling and slidable adjustment.

Because of the thermal conductivity of the metal parts 3 and 5, the thermostatic arm 19 is efficiently temperature responsive not only to resistance-induced heat caused by current passing through it, but also to the ambient temperature. The switch accordingly functions effectively to protect motor windings when interstitially located in respect thereto. By connecting terminals 9 and 11 in the motor circuit, operation of the thermostatic switch will interrupt the current to the motor not only when the current reaches an undesired value but also when the motor windings become overheated for any other cause.

The switch of the present invention has minimum heat mass and minimum size, leading to quick heat response. Such quick heat responses are very valuable and are critical in certain motor protection applications.

The switch is shown in greatly enlarged scale in the drawings. In actual practice it may be approximately one-fifth the size shown in the original drawings on file in the Patent office so that it is conveniently insertable at or in the motor winding which it is designed to protect.

Although the insulating washer member 13 is conveniently attached to both parts of the container by means of a separate adhesive, it may, if desired, be pressure sensitive or composed of an adhesive material per se. Although the thermostatic member 19 is preferably snap acting, a creep acting thermostatic element may be employed, if desired.

Since the switch is sealed during manufacture it may be placed on a motor winding and the winding subse-

quently processed as by dipping and baking. Thus the switch and winding assembly may be dipped and baked as a unit without danger of the dipping compound penetrating into the switch. The switch of the present invention being a sealed device, can, therefore, be assembled into motors at the desired stage so as to become an integral part thereof.

From the foregoing, it will be clear that the switch of the present invention is constructed of only a few simple parts which may be easily assembled to form a device which can be calibrated during manufacture and remains protectively sealed during use. The switch is accordingly inexpensive to manufacture yet is effective for the purpose intended.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A thermostatic switch comprising two conductive members shaped to form a hollow capsule when assembled, and providing line connections, an insulating member sandwiched between said members and attached thereto by means of a set synthetic resin to form a seal, said insulating member having an opening therethrough, and a snap-acting thermostatic member attached to one of said conductive members and supporting a contact engageable and disengageable interiorly with the other one of said conductive members, said thermostatic member extending operatively through said opening, each of said conductive members having a marginal flat-flange means for engagement with said insulating member around said opening, whereby one conductive member shall have been slidable relative to the other on opposite sides of the insulating member prior to setting of said resin to adjust the relationship between said contact and said other conductive member, said other conductive member being provided with a portion extending toward and adjacent the contact on the thermostatic member, whereby through sliding prior to resin setting one of various possible contact pressures inheres at a given temperature after the resin has set.

2. A thermostatic switch according to claim 1, wherein said extending portion is constituted by a contact-forming sloping portion of said other conductive member.

3. A thermostatic switch according to claim 1, wherein said extending portion is constituted by a dimple in said other conductive member.

4. A thermostatic switch according to claim 1, wherein said capsule-forming conductive members include projecting ear-forming parts for making electrical connections.

5. A thermostatic switch according to claim 4, including a winding around said ear-forming parts.

6. A thermostatic switch comprising two assembled conductive members shaped to form when assembled a hollow capsule providing line connections, an insulating and sealing member sandwiched between said members and attached thereto by a cured synthetic resin, said insulating member having an opening therethrough, a thermostatic member conductively attached to one of said conductive members and supporting a contact engageable and disengageable interiorly with the other one of said conductive members, said thermostatic member extending through said opening, each of said conductive members being marginally provided with relatively slidable engaging flange means shaped for sealing engagement with said insulating member around said opening in all relative sealing positions of the flange means, whereby one conductive member shall have been slipped relative to the other dur-

ing assembly with said sealing member and prior to curing of said resin to adjust the contact relationship between said contact and said other conductive member, said other conductive member being formed with an engageable contact surface adjacent said contact.

7. A thermostatic switch construction comprising two conductive members shaped when assembled to form a hollow capsule providing line connections, an insulating and sealing member sandwiched between said members and attached thereto by a set synthetic resin, said insulating member having an opening therethrough, a thermostatic member conductively attached to one of said conductive members and supporting a contact engageable and disengageable interiorly with the other one of said conductive members, said thermostatic member extending through said opening, each of said conductive members being provided marginally with substantially flat-flange means for engagement with said insulating member around said opening, whereby one conductive member is adapted to be slipped relative to the other during assembly with said sealing member and prior to setting of said resin to adjust the contact relationship between said contact and said other conductive member.

8. A thermostatic switch construction comprising two conductive members relatively slidable on a plane of slip and shaped when assembled to form a hollow capsule providing line connections, an insulating and sealing member sandwiched between said conductive members and attached thereto by a settable synthetic resin, said insulating member having an opening therethrough, a thermostatic member conductively attached to one of said conductive members and supporting a contact engageable and disengageable interiorly with the other one of said conductive members, said thermostatic member extending through said opening, said other conductive member being formed with a sloping surface adjacent said contact, which surface slopes relative to the plane of slip, whereby desired contact pressure is obtained after setting of said resin.

9. A thermostatic switch construction comprising two conductive members shaped when assembled to form a switch body having line connections, a thermostatic member conductively attached to one of said conductive members and supporting a movable contact engageable and disengageable interiorly with the other one of said conductive members, an insulating member sandwiched between said members and attached thereto by an initially flowable but finally set resin, said insulating member and said conductive members being shaped for relative movements of said conductive members on opposite sides of the insulating member when the resin is in flowable form, said insulating member forming a passage for said thermostatic member, said thermostatic member extending across said insulating member at said passage, said other conductive member being formed with a fixed contact adjacent said movable contact.

10. A thermostatic switch comprising two conductive housing parts having adjacent rims and shaped to form a hollow capsule, sealing and holding means between the rims comprising an initially flowable but finally set electrically insulating resin, a movable conductive thermostatic member in direct conductive contact with one of said conductive housing parts, the other conductive housing part being formed with a sloping surface, said thermostatic member having a movable portion carrying a contact engageable and disengageable with said sloping surface of said other part, said parts being adapted for relative sliding movement when said resin is flowable, whereby the contact pressure between said contact and said sloping surface may be varied when said resin is flowable, said resin electrically insulating said conductive housing parts from each other.

11. A thermostatic switch according to claim 10, wherein the thermostatic member is of the snap-acting type, and wherein said sealing means includes a washer forming part of the sealing means and is held by said resin between

said rims, said washer including an opening through which said thermostatic member extends.

12. A thermostatic switch according to claim 11, where-in portions of said rims and of said washer therebetween have extensions, the rim extensions sandwiching the washer extensions, and including switch terminal portions projecting from the rim extensions.

13. A thermostatic switch comprising two conductive housing parts having adjacent rims and shaped to form a hollow capsule, sealing and holding means between the rims comprising an initially flowable but finally set resin, a conductive thermostatic member in direct conductive contact with one of said conductive housing parts and having a movable portion carrying a contact engageable and disengageable with the other conductive housing part, said thermostatic member being of the snap-acting type, said sealing means including a washer forming part of the sealing means, said washer being held by said resin between said rims, said washer including an opening through which said thermostatic member extends, portions of said rims and of said washer therebetween having extensions, the

rim extensions sandwiching the washer extensions, switch terminal portions projecting from the rim extensions, and a mass of insulating material surrounding said rim and washer extensions, said washer and resin forming an electrically insulating barrier between said conductive housing parts.

14. A thermostatic switch according to claim 13, where-in said mass is constituted by a wrapping of insulating tape.
